CLAIM

The ornamental design for a tray insert, as shown and described.

DESCRIPTION

FIG. 1 is a perspective view of a tray insert showing a new design;

FIG. 2 is a front elevation view thereof, the rear being a minor image;

FIG. 3 is a left side elevation view thereof, the right side being a mirror image;

FIG. 4 is a top plan view thereof;

FIG. 5 is a bottom plan view thereof;

FIG. 6 is another perspective view of the tray insert of FIG. 1 shown as installed in a carton;

FIG. 7 is a front elevation view thereof, the rear being a minor image;

FIG. 8 is a left side elevation view thereof, the right side being a mirror image;

FIG. 9 is a top plan view thereof; and,

FIG. 10 is a bottom plan view thereof.

The tray insert is shown with a symbolic break in its length. The appearance of any portion of the article between the break lines forms no part of the claimed design. In FIGS. 6–10, the broken lines show portions of a carton that form no part of the claim.
